UNITED STATES PATENT OFFICE.

ROBERT P. CALLARD, OF CHARLESTON, WEST VIRGINIA, ASSIGNOR TO THE LIBBEY-
OWENS SHEET GLASS COMPANY, OF TOLEDO, OHIO, A CORPORATION OF OHIO.

DRAWING CONTINUOUS SHEET GLASS.

Original application filed August 11, 1919, Serial No. 316,638. Divided and this application filed March 3, 1921. Serial No. 449,358.

To all whom it may concern:

Be it known that I, ROBERT P. CALLARD, a citizen of the United States, residing at Charleston, in the county of Kanawha and 5 State of West Virginia, have invented new and useful Improvements in Drawing Continuous Sheet Glass, of which the following is a specification.

This invention relates to an improvement 10 in the art of drawing glass in sheet form from a mass of molten glass, and is concerned particularly with a process for drawing the sheet by means applied only to the side edges thereof, leaving the central body 15 portion of the sheet entirely free and exposed throughout the drawing process. This invention was first disclosed in my copending application, Serial Number 316,638, filed August 11, 1919, of which this present application 20 is a division.

The specific character of the invention, and the objects and advantages attained thereby, will be better understood from the following detailed description of a form of 25 apparatus adapted to carry out this invention.

In the accompanying drawings:

Fig. 1 is a front elevation of the sheet drawing mechanism, the receptacle from 30 which the sheet is drawn being shown in vertical section.

Fig. 2 is a side elevation of one of the edge drawing mechanisms, the sheet and receptacle being shown in vertical section substantially on the line 2-2 of Fig. 1.

Fig. 3 is an enlarged view, similar to Fig. 2, of the lower portion of the drawing mechanism.

The shallow draw-pot or receptacle 1, is 40 continuously supplied with molten glass 2, from a suitable source, such as a continuous tank furnace. A heating chamber beneath the draw-pot is indicated conventionally at 3. The sheet of glass 4 is drawn vertically 45 upward from the molten glass 2 in receptacle 1.

At each edge of sheet 4 is arranged a drawing and width maintaining mechanism 5, the two mechanisms being substantial duplicates, so that only one of them need be described in detail. A pair of endless chains 6 and 7, mounted to travel in substantially 50 the same vertical plane, travel one at each side of the edge portion of the sheet of glass,

and the links of the chains carry on their outer sides gripping members 8, which preferably have their faces roughened or knurled to more positively engage the glass sheet. The inner runs of the chains are so spaced that the sheet will be gripped and carried along between adjacent pairs of grippers 8. The chains 6 and 7 are each carried on sprockets 9 at their lower ends, and 10 at their upper ends, the sprockets 9 and 10 being mounted on and keyed to short horizontal shafts having bearings in the supporting frame 11. The two upper shafts, carrying sprockets 10, are geared together for simultaneous but opposite rotation, by the intermeshing spur gears 12, and one of the shafts carries a bevel gear 13 at its outer end meshing with a bevel gear 14 on the vertical drive shaft 15, also carried by frame 11.

The inner sheet engaging runs of the chains 6 and 7, are held yieldingly against the sheet by guide bars 16, which are pressed inward by expansion springs 17, held between the bars and adjusting screws 18 threaded into bosses 19 extending from the frame 11.

The frame 11 is mounted on a truck 21, movable toward and from the edge of the sheet on trackways 22, the forward wheels 23 being mounted directly on the truck, whereas the rear wheels 24 are carried by swinging levers 25, pivoted to the truck body at one end, and at the other end having adjusting screws 26 bearing against the lower side of extensions 27 on the truck body. By suitably adjusting the screws 26, the truck and frame 11 and parts carried thereby may be tilted so as to properly align the drawing chains or gripping members with the edge of the sheet. By tilting the frames inward, a certain amount of contraction of the sheet as it cools may be allowed for. By moving the trucks in or out along the trackways 22, the grippers may be brought into or out of drawing position over receptacle 1, or adjusted for different widths of sheets.

The drive shafts 15 for the two drawing mechanisms, extend down between the rails 22, and are connected by bevel gearing 28 and 29, with a horizontal drive shaft 30, which derives its power from any suitable source, as indicated at 31. The shaft 30 is divided and has an extendable connection

32, whereby the length of the shaft may be varied, to allow for the separation of the drawing mechanisms, as already described.

At 33 are indicated suitable edge forming rollers, each preferably having a knurled surface, between which the edge portions of the sheet are rolled and fed up from the molten glass. These rolls 33 are preferably driven from the same source of power as the drawing members 8, and at a peripheral speed somewhat less than the linear speed of the chains, so that the sheet will be stretched longitudinally between rolls 33 and the drawing mechanisms. As shown in the drawings, the rolls are geared together by intermeshing spur-gears 35, and one of these gears 35 is driven from the adjacent lower sprocket shaft through the train of gears 36 and 37.

Although this drawing mechanism might be successfully operated in the open air, or in a partially enclosed space, it is illustrated in Figs. 2 and 3, as mounted in an enclosing chamber 34. In this arrangement, the faces of the sheet 4, which are entirely exposed, since the drawing mechanisms engage the sheet only at the edge portions, will be open to the tempering action of the heated gases and radiant heat in the chamber 34.

The drawing of the sheet is initiated by lowering a suitable bait into the molten mass 2 and slowly pulling this bait and attached sheet up and through the drawing mechanisms 5. The bait is then detached, and the sheet will be continuously drawn up through these devices, and may be cut off, in the desired sections, above the drawing mechanisms. It will be noted that nothing engages the central body portion of the sheet at any time, thus always leaving the sheet unmarred and entirely exposed to the tempering actions of the heated gases thereabout. It will also be noted that the drawing mechanisms engage the sheet edges throughout a considerable vertical area, and the sheet through the upper portion of this area becomes hard and set so that it acts as a bait to draw up the continually added portion from the molten mass below.

Obviously a drawing mechanism of this type might be adapted for use with a down pulled sheet as well as one drawn vertically upward.

Claims:

1. In a sheet drawing machine, a receptacle containing molten glass from which the sheet is drawn, means for engaging and moving with each edge of the sheet until the sheet has become set for drawing the sheet from the receptacle, pairs of edge forming rollers engaging each edge of the sheet between the molten glass and the edge drawing mechanisms, and means for simultaneously and synchronously driving the two

edge drawing mechanisms, the edge forming rolls being driven from the same source.

2. In a sheet glass drawing machine, a pair of vertically moving chains at each edge of the sheet, gripping the opposite sides of the edge portion only and drawing the sheet upwardly, each pair of chains being mounted on a truck movable in and out in the plane of the sheet, and means simultaneously and synchronously driving the two pair of chains. 70

3. In a sheet glass drawing machine, a pair of vertically moving chains at each edge of the sheet, gripping the opposite sides of the edge portion only and drawing the sheet upwardly, each pair of chains being mounted on a truck movable in and out in the plane of the sheet, means for tilting the trucks to incline the chains inwardly to allow for the shrinkage of the sheet, and means for simultaneously and synchronously driving the two pair of chains. 80

4. In combination, means to hold a supply of molten glass from which the glass sheet is formed, a pair of opposed chains at each edge of the sheet for gripping the sheet and continuing in gripping engagement therewith during a predetermined length of movement of the sheet, and separate means carrying and guiding the movements of the pairs of chains and adjustable to dispose the sheet gripping flights of the chains parallel to the longitudinal centerline of the sheet or at an angle thereto. 90

5. In combination, means to hold a supply of molten glass from which the glass sheet is formed, a pair of opposed chains at each edge of the sheet for gripping the sheet and continuing in gripping engagement therewith during a predetermined length of movement of the sheet, and separate means carrying and guiding the movements of the pairs of chains, said separate means being swingingly adjustable toward and away from each other to vary the line of movement of the gripping portions of the chains with respect to the longitudinal centerline of the sheet. 100

6. In combination, means to hold a supply of molten glass from which the glass sheet is formed, a pair of opposed chains at each edge of the sheet for gripping the sheet and continuing in gripping engagement therewith during a predetermined length of movement of the sheet, separate means carrying and guiding the movements of the pairs of chains and adjustable to move the chains together inward or outward to suit the line of movement of the sheet, and means operable to impart feeding movements to the chains of each pair in any position of adjustment of the chains. 115

7. In combination, means to hold a supply of molten glass from which the glass sheet is formed, a pair of opposed chains 120

at each edge of the sheet for gripping the sheet and continuing in gripping engagement therewith during a predetermined length of movement of the sheet, separate means carrying and guiding the movements of the pairs of chains and adjustable to dispose the sheet gripping flights of the chains parallel to the longitudinal center line of the sheet or at an angle thereto, and means operable to impart feeding movements to the chains of each pair in any position of adjustment of the chains.

8. In combination, means to hold a supply of molten glass from which the glass sheet is formed, a frame adjacent to each side edge of the sheet and near the sheet source, each frame mounted for angular adjustment transverse to the sheet, means for imparting angular adjustment to each frame, two sets of upper and lower shafts carried by each frame, an endless chain connecting the shafts of each set and driven by one shaft

of the set, said chains having prolonged gripping coaction with the adjacent edge of the sheet to serve as width maintaining means therefor, and means for driving one shaft of each set to impart opposed driving movements to the chains.

9. In combination, means to hold a supply of molten glass from which the glass sheet is formed, a frame adjacent to each side edge of the sheet and near the sheet source, each frame being mounted for angular adjustment transverse to the sheet, means carried by each frame including opposed chain sets for prolonged gripping coaction with the adjacent edge of the sheet, and means for driving the chains of each set.

Signed at Charleston, in the county of Kanawha and State of West Va., this 26th day of February, 1921.

ROBERT P. CALLARD.
